UNITED STATES PATENT OFFICE.

CHARLES M. TRUNDE AND EDGAR T. MILLS, OF MILLVILLE, WEST VIRGINIA.

RAIL JOINT.

Application filed December 19, 1924. Serial No. 756,965.

To all whom it may concern:

Be it known that we, CHARLES M. TRUNDE and EDGAR T. MILLS, citizens of the United States, residing at Millville, in the county of Jefferson and State of West Virginia, have invented certain new and useful Improvements in Rail Joints, of which the following is a specification.

This invention relates to improvements in rail joints of the type in which the rails are joined without the employment of bolts, and one of the objects of the present invention is to provide a rail joint of this type of such construction that the use of bolts is entirely obviated as well as the use of keys, pins, or other initially loose and separate fastening elements for connecting the fish plates to the rails, the invention contemplating the employment of means at all times fixed with relation to the rail ends, for so securing the parts.

Another object of the invention is to provide a novel construction and arrangement of the fish plates such that the plates may be readily loosened and removed by merely striking one end thereof and without disturbing the connecting elements with which they have been associated, which, however, is necessary where such elements are separate from the rails and fish plates as is usually the case.

Another object of the invention is to provide a rail joint so constructed that by merely extracting the spikes which secure the fish plates to the ties, the fish plates may be completely separated from the rails by merely striking one end of each plate, thereby greatly facilitating the application and removal of the fish plates to and from the rails.

In the accompanying drawings:

Figure 1 is a side elevation of the rail joint embodying the invention, installed.

Figure 2 is a horizontal sectional view taken substantially on the line 2—2 of Figure 1, looking in the direction indicated by the arrows.

Figure 3 is a vertical transverse sectional view taken substantially on the line 3—3 of Figure 1, looking in the direction indicated by the arrows.

The rails, indicated in the drawings by the numeral 1, comprise the usual base flange 2, web 3, and head 4, and the rails do not differ from ordinary rails except that their customary bolt openings 5 are occu-

pied by the intermediate portions of double-ended studs which are indicated in general by the numeral 6 and constitute the means for holding the fish plates, indicated by the numeral 7, to the rail ends. Each of the studs 6 comprises a shank 8, formed at a point midway between its ends with a cylindrical enlargement 9 which is forced into position within the respective opening 5 and, when forced into place, becomes practically an integral part with the web of the rail with which it is associated. The shank 8 is provided at each end with a head 10 which is preferably of circular form and which has its face which is presented toward the enlargement 9, disposed at an oblique angle to the axis of the shank, as indicated by the numeral 11. The oblique faces 11 of the heads 10 occupy vertical parallel planes with respect to each other and, consequently their faces are disposed at opposite angles to the web 3 of the rail to serve a purpose to be presently pointed out.

The fish plates 7 are of counterpart construction and, so far as their general contour is concerned, do not differ from fish plates now in use, each plate comprising the usual upstanding body portion 12 for disposal against the webs of the rails to be joined, and the usual base flange 13 to rest upon the base flanges of the said rails, the base flange of each fish plate being provided with the usual notches 14 to accommodate the spikes 15 which are driven through the usual tie plate 16 and into the ties to secure the fish plates in place. Each fish plate is formed with a suitable number of openings to receive the headed projecting ends of the studs 6, and each opening, indicated by the numeral 17, is preferably of the elongate form shown in Figure 1 of the drawings, the openings being of a height greater than the diameter of the heads 10 of the studs and of a length preferably somewhat greater than their height, so as to compensate for any variations in the distance of projection of the extremities of the rails beyond the endmost studs. Each opening 17 has a longitudinal extension 18 of a height to more or less snugly accommodate the portion of the shank of the respective stud 6 inwardly of the head 10, and the extensions 18 of the openings are all presented toward the same end of the fish plate in which they are formed, or, in other words, all extend in the same direction and in horizontal alinement

parallel to and between the upper and lower edges of the body portion 12 of the fish plate. The outer face of the body portion 12 of the fish plate is formed with a recess 19 at that end of the opening 17 from which the extension 18 extends, and the side walls of the recess, indicated by the numeral 20, are beveled so as to provide wedging faces above and below the extension 18, these faces 10 gradually merging with the outer face of the body member 12 of the fish plate at a point adjacent the end of the extension 18 and the angular disposition of the faces being substantially the same as the faces 11 15 of the stud heads 10 so that the faces of the said heads 10 may coact with the wedging faces 20 when the fish plate is disposed against the sides of the rails and slid into the position shown in Figures 1 and 2 of the drawings. It will be observed by reference to Figure 2 of the drawings that when the fish plates are disposed against opposite sides of the meeting ends of two rails to be joined, the corresponding wedging faces 20 25 beside the openings 17 will occupy parallel vertical planes coincident with the planes occupied by the inclined or oblique faces 11 of the heads 10 of the studs 6, when the fish plates are slid to bring the said faces 20 into wedging engagement with the faces 11. In assembling the fish plates with the rails, the fish plates are, of course, first disposed so that the heads of the studs will project through the openings 17 and the fish plates 30 are then slid longitudinally, the plates being, however, slid in opposite directions due to the reverse inclination of the faces 11 of the heads of the studs. When the plates have been shifted as far as possible, manually, each plate is struck one or more blows 40 with a sledge, at that end toward which the extensions 18 of the openings are presented,

thereby firmly wedging the faces 20 into engagement with the faces 11 and firmly binding the fish plates to the rails. The 45 spikes 15 are then driven into place and in this manner the rails are firmly joined at their meeting ends and securely held against any relative displacement which would throw them out of alinement. 50

It will be evident that in order to remove the fish plates, it is only necessary to withdraw the spikes 15, whereupon a blow may be struck against that end of each fish plate opposite the end referred to above so as to 55 shift the plate out of engagement with the heads of the studs.

Having thus described the invention, what we claim is:

1. A rail joint fastening consisting of a 60 stud having a medial cylindrical enlargement and similar heads at opposite ends, the inner faces of the heads being parallel and reversely inclined.

2. A rail joint comprising adjacent rail 65 ends having openings in their webs, a stud for each of the openings secured therein by a medial cylindrical enlargement and having similar heads at opposite ends with their inner faces parallel and reversely inclined, 70 and fish plates at the sides of the joint provided with longitudinally elongated openings for the free passage of the stud heads, and having an end portion of each of the openings constricted and the outer side of 75 the fish plate recessed at each side of the constricted portion of the openings and longitudinally inclined to correspond with the inclined face of the adjacent stud head to coact therewith by a wedging action. 80

In testimony whereof we affix our signatures.

CHARLES M. TRUNDLE. [L. s.]
EDGAR T. MILLS. [L. s.]
